UNITED STATES PATENT OFFICE.

HERMANN A. KNOENER, OF EAST ORANGE, NEW JERSEY, ASSIGNOR TO CROCKER-WHEELER COMPANY, OF AMPERE, NEW JERSEY, A CORPORATION OF NEW JERSEY.

COMMUTATOR.

SPECIFICATION forming part of Letters Patent No. 783,965, dated February 28, 1905.

Application filed July 25, 1904. Serial No. 218,051.

To all whom it may concern:

Be it known that I, HERMANN A. KNOENER, a citizen of the United States of America, and a resident of East Orange, county of Essex, and State of New Jersey, have invented certain new and useful Improvements in Commutators, of which the following is a specification.

The object of this invention is to produce a commutator the construction of which is such that structural materials of greater strength and yet of less expensive character may be used and the parts may be more readily and firmly assembled.

The commutator is cylindrical and is provided with commutator-bars such as are ordinarily employed in dynamo-electrical machinery, wherein the commutating-surfaces of the bars form the surface of a cylinder and each bar lies along an element of the cylinder. The ends of the commutator-bars are clamped between flanges, and the flanges are screwed on reversely-threaded ends of a central tube, thereby holding the bars in place.

Referring to the accompanying sheet of drawings, which form a part of this application, Figure 1 is an end view of my commutator. Fig. 2 is a longitudinal section on the line II-II of Fig. 1. Figs. 3 and 4 are longitudinal sections through the clamping-flanges. Fig. 5 is a side view of the central tube. Fig. 6 is a perspective view of one of the commutator-bars.

The commutator as illustrated in the drawings consists of a series of copper bars A of wedge-shaped section assembled with interposed insulation M, usually mica, so as to form a cylindrical commutating-surface, the bars being parallel to the axis of the cylinder and lying along parallel elements thereof, with the wide edges c forming the commutator-surface. The ends of the bars are provided with notches or V-grooves m. The bars are assembled about a tube or sleeve B. The tube is cut to suitable length from accurately-drawn steel tubing of regular commercial sizes, which possesses greater tensile strength and costs less than cast-steel requiring to be turned,

which has heretofore been employed in commutator constructions wherein the designs 50 have required that one flange be integral with the sleeve. The ends of the tube are reversely threaded, a right-hand screw-thread r being cut on the tube on one end and a left-hand screw-thread l being cut on the tube on 55 the other end. Flanges R and L, preferably of bearing metal such as brass or bronze, in the form of nuts tapped with right-hand and left-hand threads, respectively, are screwed on the ends of the tube. Circular ribs t project 60 from the sides of the flanges and are covered with insulating material M', preferably mica. The ribs project into the notches in the ends of the commutator-bars, the mica being, however, interposed, and support the bars. By 65 reason of the reverse threading of the two flanges they can be tightened simultaneously on the commutator-bars by rotation relatively to the tube in the same direction or preferably by holding both flanges from rotation while the tube is revolved. It therefore follows that the clamping is effected without danger of dragging the commutator-bars and skewing them around at an angle, so that they will be out of parallelism with the axis 70 of the commutator. There is no danger of injuring the interposed mica between the flanges and bars since there is no relative movement between these. Attention is also called to the fact that there is no sliding of contacting surfaces of parts relatively to each other except at the screw-threads, and there is avoidance 75 of all frictional action at a greater distance from the axis than the screw-threads in tightening the parts such as takes place when a 80 nut is screwed against a flange or washer. As the threads are nearer to the axis, there is less leverage and sliding movement, and the flanges are more readily and more firmly set up against the commutator-bars with the application of 85 a given amount of turning force. The tube is notched at k to fit over a pin in the armature-shaft on which the commutator is placed.

One end of each commutator-bar is slotted, as shown at v in Figs. 2 and 6, for the insertion and soldering therein of connections from 90 95

the commutator-bars to the coils of the armature.

What I claim as new, and desire to secure by Letters Patent of the United States, is—

5 1. A cylindrical commutator consisting of a series of commutator-bars, a central tube reversely threaded on its two ends, and flanges screwed on the threaded ends of the tube and clamping the ends of the commutator-bars, substantially as described.

10 2. A cylindrical commutator consisting of a series of commutator-bars, a central tube reversely threaded on its two ends, metal flanges

screwed on the threaded ends of the tube and clamping the ends of the commutator-bars, ¹⁵ and insulating material interposed between the flanges and the bars, substantially as described.

Signed by me at East Orange, county of Essex, and State of New Jersey, this 16th day ²⁰ of July, 1904.

HERMANN A. KNOENER.
